ELECTRIC CURRENT CONTROL DEVICE

Roberto J. Peralta, Panuco, Mexico

Application April 23, 1934, Serial No. 722,041
In Mexico May 23, 1933

3 Claims. (Cl. 200—122)

The invention relates to an electric current control device and more especially to a circuit breaker and closer.

The primary object of the invention is the provision of a device of this character, wherein the passage of a predetermined amount of electric current therethrough is permitted by the breaking of the circuit when an overload of the current occurs, the said device being readily operative for the automatic closing of the circuit when the overload ceases.

Another object of the invention is the provision of a device of this character, wherein the same is susceptible of substitution for a fuse and will operate to control the current in an electric circuit, as the same will operate to permit only the passage of a predetermined amount of electric current and the opening or breaking of the circuit when an overload occurs, the device being novel in form.

A further object of the invention is the provision of a device of this character which is simple in construction, thoroughly reliable and efficient in its purpose, durable, readily and easily engaged in a fuse socket arranged in an electric circuit, and inexpensive to manufacture.

With these and other objects in view, the invention consists in the features of construction, combination and arrangement of parts as will be hereinafter more fully described in detail, illustrated in the accompanying drawing, which discloses the preferred embodiment of the invention, and pointed out in the claims hereunto appended.

In the accompanying drawing:

Figure 1 is a vertical longitudinal sectional view through a device constructed in accordance with the invention, the device being shown by full lines in circuit closing position and by dotted lines in opening position.

Figure 2 is a side elevation partly in section showing a slight modification of the device.

Figure 3 is a view similar to Figure 1 showing a further modification of the device.

Similar reference characters indicate corresponding parts throughout the several views in the drawing.

Referring to the drawing in detail, particularly Figure 1, the device comprises a two-part shell 50 A including a hollow body 10 and a lid or cover 11, the latter being telescoped over the outer open end of said body 10 and seated against an external annular shoulder 12 on said body 10. The opposite closed end of the body 10 is reduced to form a central externally threaded hollow plug 13 for

detachable engagement in a fuse socket arranged within an electric circuit, the socket and circuit being not shown.

Within the body 10 is an insulating lining 14, while in the outer open end of said body is arranged a flexible diaphragm 15, the latter being normally in concavo-convex position within the body, and this diaphragm is held secure to the body in any suitable manner. Connected centrally with the diaphragm is a stem 16, the same 10 being extended outwardly through a suitable clearance in the cover 11 and carrying at its outer end a contact button 17 which functions as an opening and closing switch, the same being normally engaged with the cover 11, the stem 16 15 being insulated from the diaphragm through the medium of an insulator bushing 18. Mounted in the plug 13 is a post 19, the same being secured to the outer end of the plug and insulated therefrom by an insulator bushing 20. This post 19 supports within the body 10 the core or holder 21 for a coiled resistance wire 22 constituting an electric heating unit, the wire being connected at one end directly with the post 19 and its other end with a connector 23 with the stem 16. Thus 25 when the device is engaged in the fuse socket a circuit will be completed through the resistance coil 22 and body 10 when the contact button 17 is engaged with the lid or cover 11 of said body, or, in other words, when the device has its parts 30 in the position as shown by full lines in Figure 1 of the drawing. Should an overload in the circuit occur, the diaphragm 15 will be flexed or convexed and thus shift the button 17 out of contact with the cover 11 of the body 10 so that the 35 circuit will be broken.

The diaphragm 15 is flexed under the action of an expansible fluid or medium as contained within the body 10, said fluid being in the form of a gas partially filling the said body, as for 40 example, nitrogen or ozone or the like by the electric heating unit 22 for the expansion thereof. When this medium cools, the device operates to close the circuit, especially on relieving the 45 overload in the circuit.

In Figure 2 of the drawing there is shown a slight modification of the invention, wherein the stem 24, alike to the stem 16, has surrounding it the coiled compression spring 25, the same being seated at one end against the insulator bushing 50 26 at the point of connection of the stem with the flexible diaphragm 27 and the other end against an insulator sleeve 28 fitted in the clearance for the stem 24 as provided in the cover of the device and this spring augments the diaphragm 27 to 55

cause the same to flex into concavo-convex formation, this being the normal condition thereof with the electric circuit closed.

In Figure 3 of the drawing there is shown a still further modification of the invention, wherein in the resistance wire 29 is suspended within the device and connected directly to the post 30 and the stem 31. This stem 31 carries the circuit closing button 32 and an insulated hand knob 33 having the button counterseated therein. Thus the stem 31 can be manually manipulated for the opening and closing of the circuit. However, normally the circuit is closed and when the same is automatically opened the stem can be manually operated for resetting the device to circuit closing position.

What is claimed is:

1. A device of the character described comprising a screw plug body having a cover, a flexible diaphragm arranged within the body, an expansible medium held within the body for flexing the diaphragm, an electric heating unit within the body, a switch operated by the diaphragm and arranged in an electric circuit having included therein the heating unit, said switch including a stem connected with the diaphragm,
- 20
- 25

a head exteriorly of the body, and an insulating hand knob on said head.

2. A device of the character described comprising a screw plug body having a cover, a flexible diaphragm arranged within the body, an expansible medium held within the body for flexing the diaphragm, an electric heating unit within the body, a switch operated by the diaphragm and arranged in an electric circuit having included therein the heating unit, said switch including a 10 stem connected with the diaphragm, a head exteriorly of the body, a hand knob on said head, and spring means augmenting the flexible diaphragm for flexing the same in one direction.

3. A device of the character described, comprising a hollow body having a screw plug end and a cover, a flexible diaphragm arranged within the body, an expansible medium held within the body for flexing the diaphragm, an electric heating unit within the body, and a switch operated by the diaphragm and arranged in an electric circuit having included therein the heating unit, and accessible exteriorly of said body at the cover side thereof.
